STORE FRONT

Jerome Gould, Los Angeles, Calif., assignor to A & W Root Beer Co., Santa Monica, Calif., a corporation of California

Filed July 13, 1964, Ser. No. 80,830

Term of patent 14 years

(Cl. D13—1)

I claim:

The ornamental design for a store front, substantially as shown.
